UNITED STATES PATENT OFFICE.

WILLIAM ADDISON WHEELOCK, OF NEW YORK, N. Y.

BOTTLE TOP AND LOCK.

1,358,352.

Specification of Letters Patent.

Patented Nov. 9, 1920.

Application filed November 26, 1919. Serial No. 340,741.

To all whom it may concern:

Be it known that I, WILLIAM A. WHEELOCK, a citizen of the United States, and a resident of the city of New York, borough 5 of Manhattan, in the county and State of New York, have invented a new and useful Bottle Top and Lock, of which the following is a full, clear, and exact description.

This invention relates to bottle closers and 10 particularly to an improved closer or cover which acts in the double capacity of a cover and as a lock.

The object in view is to provide a combined cover and lock for a bottle or similar 15 receptacle which is in the nature of a combination lock whereby it cannot be removed until the combination has been properly actuated.

Another object in view is to provide a 20 closer for a bottle wherein the neck of the bottle is formed with a stepped construction and a corresponding shaped cap is provided together with locking means for holding the cover in place.

25 A still further object is to provide a combination lock with a cover or cap for bottles or other receptacles wherein a plurality of combinations may be used and holding means associated therewith to prevent accidental shifting of any part.

In the accompanying drawing:

Figure 1 is a perspective view showing part of a bottle with an embodiment of the invention applied thereto, the same being partly broken away for better illustrating the construction.

Fig. 2 is an enlarged fragmentary sectional view through Fig. 1, approximately on line 2—2.

40 Referring to the accompanying drawing by numerals, 1 indicates a bottle of any desired kind provided with a neck 2 which merges into a head 3 having an opening extending centrally therethrough, which is adapted to receive a stopper 4 of any desired material, as for instance an ordinary cork. This cork may be applied and removed easily, but in order to prevent such removal by an unauthorized person the cap 5 is supplied, which interlocks with parts of the head 3 so as to protect the stopper.

From Fig. 1 it will be noted that the head 3 is provided with a stepped formation, wherein three shoulders, 6, 7 and 8, are presented, though a greater or even less number could be used without departing from the

spirit of the invention. The cover 5 is formed with the same number of shoulders as the head 3 so as to conform therewith. It will be observed that the respective shoulders are provided with annular grooves, 9, 10 and 11, and with vertical grooves 12, 13 and 14, extending from the top of the respective shoulders downwardly into the respective grooves so that the various pins 15 may pass through the various vertical grooves into the horizontal grooves and then partially around the horizontal grooves for producing a locking action for the various sections 16, 17 and 18. These sections are 70 independently movable and are connected by having a bead 19 adjacent the bottom of each section and a turned-in flange 20 whereby a guiding groove is formed through which the next adjacent section moves. 75

Arranged on each of the sections is a series of numbers 21, co-acting with the respective plungers 23. These plungers are 80 slidably mounted in suitable holders 24, soldered or otherwise secured in place and carry springs 25 to resiliently hold the plunger 23 in a lowered position. Arranged on the neck 2 at a convenient point is a line or indication 26, which is to line up with certain of the numbers 21 on the section 85 16. The numbers on section 17 line up in any predetermined manner with the numbers on section 16, while the numbers 21 on section 18 are designed to be lined up with the numbers on section 17, according 90 to the particular combination used.

As shown in the drawing, the combination is such so that when the number 1 is in line with the designation 26, pin 15 on section 16 will be in line with the vertical 95 slot 12. When the numeral 4 is in line with 0 on section 16 the pin 15 on section 17 will be in line with the vertical slot 13, while pin 15 will be in line with the slot 14 when the numeral 1 is in line with 4 on section 17. It is evident, of course, that the numbers 21 on the various sections could be re-arranged at any time so as to change the combination. After the combination has been once set the cover 5 may be easily removed by a vertical pull, as all the pins 15 are in line with the respective vertical slots. After the cover has been replaced the same will be locked by turning any one section, though it is preferable ordinarily to turn 110 all three sections. By providing the plunger 23 the sections are locked against ac-

cidental turning whereby when the cap is removed it will remain in proper position to be readily and quickly applied.

What I claim is:

- 5 1. A combination cover and lock for bottles comprising a head for a bottle formed with a plurality of shoulders, each shoulder having an annular groove and a vertical groove, a cap having a stepped formation fitting the shouldered formation of said head, each of the steps of the cap being independently rotatable, and a locking pin or bolt connected with each of said steps adapted to pass through said vertical 10 grooves into the annular grooves whereby when any of said pins are moved out of alignment with their vertical grooves the cap is locked in position.
- 15 2. A combination lock and cover for bottles comprising a head for the bottle formed with a stepped formation producing a shouldered structure, each of the steps of the stepped formation having an annular groove, a vertical groove extending from the top edge of the step to the annular groove, a cap for said head having a stepped formation, each of the steps being independently rotatable, a pin extending from each of said steps adapted to pass through

the respective vertical grooves into the horizontal grooves so that when turned out of alignment with the vertical grooves a locking action will result, and a spring pressed plunger for temporarily locking the sections in any adjusted position. 30

3. A combination lock of the character described comprising a head for a bottle having a stepped construction, the steps thereof being annular and formed with a horizontal annular groove and a vertical 40 groove, said head having a passageway therethrough for receiving a stopper, a cap of metal fitting over said head and conforming substantially to the shape thereof, said cap being constructed in independent 45 sections independently rotatable but connected together, a locking pin extending inwardly from each of the sections of the cap, said pins being adapted to pass vertically through the vertical slots and then horizontally into the horizontal slots for locking the cap against movement, a plurality of indicating legends on each section of said cap, an indicating legend arranged at the bottom of the head, and resilient means for 50 temporarily locking the sections of said cap against accidental movement. 55

WILLIAM ADDISON WHEELOCK.
